PAD HOLDER

Filed May 31, 1929

Inventor:

Charles D. Karr
By *Gillson, Mann & Cox Attnys*

UNITED STATES PATENT OFFICE

CHARLES D. KARR, OF HOLLAND, MICHIGAN

PAD HOLDER

Application filed May 31, 1929. Serial No. 367,193.

This invention relates to bed mattresses and more particularly to means for holding a plurality of pads or mattress members in assembled relation.

5 The principal object of the invention is the provision of new and improved means for connecting a plurality of pads or a pad and mattress together in such a manner as to hold them in alinement or in assembled relation 10 during use.

Another object of the invention is the provision of a new and improved means for holding a plurality of pads, mattresses, or pads and mattresses as a single unit that is 15 simple in construction, easily assembled, cheap to apply to pad or mattress, and that is efficient and reliable in use.

Other and further objects and advantages of the invention will appear from the following description taken in connection with the accompanying drawings, in which

Fig. 1 is a perspective view of the mattress and pad assembly;

Fig. 2 is a perspective view of the pad, with 25 parts broken away;

Fig. 3 is a side elevation of one corner of the pad with parts broken away;

Fig. 4 is a diagrammatic view of a hospital bed showing the invention in position there- 30 on.

Referring now to the drawings, the reference character 5 designates a hospital bed shown diagrammatically in Fig. 4. The bed is provided with the usual mattress supporting members 6 and 7 pivoted to the bed rail 8, and the member 9 pivoted to the member 7. The members 6, 7 and 9 are adapted to be adjusted to an alined position or to a plurality of adjusted positions, as is usual in 40 such constructions.

A mattress assembly 10 comprising a mattress 11 and a pad or mattress pad member 12 are supported on the supporting members 6, 7 and 9 as is usual in such constructions. The mattress 11 may be of any suitable construction, but preferably it is composed of a spring assembly.

Since the specific construction of the pad, the mattress or spring assembly and the mattress supporting members constitute no part

of the present invention it is not thought necessary to further illustrate or describe the same.

Hospital beds or beds for invalids are usually constructed in such a manner that the 55 entire pad and spring assembly may be made to take various desired forms for the accommodation of the patient. The head end portion 6 of the mattress supporting member, for instance, may be elevated for supporting 60 the patient in a reclining position or, if desired, the head end portion 6 may be elevated to support the patient in a reclining position and the central portion of the bed be elevated as indicated more or less dia- 65 grammatically in Fig. 4, for accommodating and supporting the legs or knees of the patient in a more or less bent position as desired.

In adjusting the bed or mattress assembly 70 10 the pad 12 is likely to become more or less displaced on the spring assembly 11. This is, of course, readily corrected if there is no patient on the bed, but with a patient on the bed it becomes not only a difficult matter to 75 properly position the pad, but it irritates and disturbs the patient.

In order to avoid this difficulty, suitable means are provided for so connecting the pad and mattress or spring assembly together as 80 to avoid displacement of the pad while adjusting the supporting members 6, 7 and 9.

In the form of construction selected to illustrate one embodiment of the invention, one of the bed members, preferably the pad 12, 85 is provided with loops or straps which are adapted to extend about the corners of the other member, as the mattress or spring assembly 11, for securing the two together as a single unit.

As shown, the pad 12 is provided with a strap 13 across each corner thereof. The strap 13 may be of fabric either single or folded and of any desired width and loose enough to form a loop portion for extending 95 about the adjacent corners of the mattress or spring assembly 11 as shown in Fig. 1. Each loop has its ends secured to the side and end of the pad respectively, and its central portion is loose enough or slack enough 100

to form a loop for extending across the corner of the mattress or spring assembly.

Preferably the loops at each end of the pad are formed from a single or continuous strap, 5 by having the ends secured to the side edges 15 of the pad and the central portion secured to the edges 16 of the end of the pad adjacent the center line of the pad.

The pad 12 is preferably though not necessarily made with a median seam extending 10 about the sides and ends of the pad, as shown at 17 and 18 in Figs. 2 and 3 of the drawings. By attaching the straps 13 to the pad at its median plane the straps may be turned from 15 one side of the pad to the other as occasion requires, thereby permitting the pad to be reversed.

When the assembly is applied to a hospital bed, the upper corners of the frame supporting members 6 may be inserted beneath the loops 13 as clearly shown in Fig. 4 of the drawings. By means of this arrangement the spring mattress 11 and pad 12 are connected to the supporting frame members 6, 25 7 and 9 so as to move therewith as a unit without becoming disarranged.

I claim as my invention:

1. In a bed assembly, a substantially rectangular mattress pad member, and means for 30 attaching the same to a mattress, said means comprising a strap member extending diagonally across each corner of said pad member, said strap members being secured to the ends and side edges of said pad member, and loose 35 or full enough between the ends to constitute loops for engaging the corners of a mattress and forming a snug fit therewith, each of said loops extending diagonally across the corresponding corner of said pad member and 40 constituting the sole means for attaching said pad member to said mattress, the loops at one end of the pad member being spaced from those at the other end.

2. In a device of the class described, a substantially rectangular pad having a seam on 45 its median plane extending about the ends and side edges of said pad and a strap member extending across each corner of said pad to form loops, the ends of said loops being 50 attached to said median seam at the sides and ends of said pad, the loops at one end of the pad being attached to said pad at points spaced from those at the other end of the pad, whereby said pad may be reversibly connected to the mattress solely by said loops.

3. In combination, a mattress member, a 55 pad member thereon, said mattress having corners, loop members connected to said pad member for engaging said corners for constituting the sole means for connecting said pad member to said mattress member, each of said 60 loop members, when in operative position, extending in a plane diagonally across the corresponding corner of said mattress and 65 across the side and end edges thereof, the

points of attachment of the loops to the side edges of said pad member at one end thereof being spaced from those at the opposite end thereof.

In testimony whereof I affix my signature. 70
CHARLES D. KARR.
